UNITED STATES PATENT OFFICE.

EDMUND WALTER BRIGGS, JR., OF LYONS, IOWA.

CHAIR.

SPECIFICATION forming part of Letters Patent No. 530,880, dated December 11, 1894.

Application filed April 27, 1894. Serial No. 509,245. (No model.)

To all whom it may concern:

Be it known that I, EDMUND WALTER BRIGGS, Jr., a citizen of the United States, residing at Lyons, in the county of Clinton 5 and State of Iowa, have invented a new and useful Chair, of which the following is a specification.

My invention relates to that class of chairs which are provided with seats and backs adjustable together, and the object of the invention is to provide superior devices for adjusting the back of the chair in unison with the adjustments of the seat. This end I attain by providing a screw-shaft having the back 15 and seat connected thereto so that one will be raised or lowered in unison with the movements of the other, all of which will be more fully described hereinafter and finally embodied in the claims.

20 In the accompanying drawings: Figure 1 represents a side elevation of a chair embodying the essentialities of my invention; Fig. 2, a vertical section thereof; Fig. 3, a cross-section on the line $x-x$ of Fig. 1; Fig. 25 4, a similar view on the line $y-y$ of Fig. 1; Fig. 5, a perspective view of the seat and back and their connecting parts, they being shown detached; Fig. 6, a perspective view of a modification, the seat being broken away; Fig. 7, 30 a horizontal section of the same, taken just below the seat; Fig. 8, a detail perspective of a varied form of the devices used for steady- 35 ing the arms of the modified form; Fig. 9, a sectional detail showing the devices for attaching the arms of such modified form to the sliding bar of the seat spindle.

Referring particularly to Figs. 1, 2, 3, 4, and 5, the reference numeral 1 indicates the legs of the chair, which legs are provided with the 40 braces 2, and with the stationary or main seat 3, all of which are of substantially the usual construction. Formed in the center of the main seat 3, and passing vertically therein, is the passage 4, which is provided with an 45 internally-threaded sleeve 5, whereby the passage is given the effect of being internally threaded. If so desired, this sleeve 5 may be dispensed with and the passage itself threaded, as will be well understood. Arranged in the passage 4 and engaging with the threads of the sleeve 5, is the vertical shaft 6, which is threaded substantially its

entire length and provided with the plain annular portions 7 and 8 at its upper and lower ends respectively.

55 9 indicates the seat proper, or that one upon which the user is seated, and this is arranged upon the upper end of the shaft 6, above the smooth portion 7, and is fixed to the shaft so as to turn therewith. Embracing the part 8 of shaft 6 is the bar 10, which allows the shaft free rotary movement therein, and which is held in place by the washers 11, arranged one on each side of the bar and, in turn, retained by the set-screw 12, passing axially into the 60 shaft's lower end and binding against the lower washer.

From the shaft 6 the bar 10 proceeds rearwardly and to a point in vertical alignment with the rear edge of the main seat 3, where 70 it is provided with the set-screw 13. The set-screw 13 is provided to secure the back 14 in place, and this is done by means of the series of vertically-aligned openings 15, formed in the back and adapted respectively for the 75 passage of the screw 13, while the back is adapted to slide in the socket 13^a secured to bar 10. By these means the back 14 may be adjusted in relation to the bar 10, and for a purpose that will hereinafter appear. 80

The back 14 passes up from the bar 10 to a point above the seat 9, and consists of a series of parallel bars, preferably five in number and curving at their upper ends outwardly and thence inwardly, and provided 85 with the rest 16 rigidly secured thereto, which forms the back proper. Located at the rear edge of the main seat 3, and embracing the back 14, is the guide 17, which is secured to the seat 3 and formed with the horizontally-aligned openings 18, through which the several rods of the back pass, and by which the back is guided in its movements.

19 indicates two set-screws, which are passed through the guide 17, and adapted to engage 90 the back, and whereby the back may be securely and rigidly fastened when so desired. Secured rigidly to the rear end of the bar 10, and arising vertically therefrom, is the rod 100 20, which passes through the eye 21, formed on the inner side of the guide 17 and projecting into the rear of the seat 3. From here the rod proceeds upwardly for a distance equal to about the length of the shaft 6, where

its upper end passes into the socket 22, of the guide 23. The socket 22 is provided with a set-screw 27, adapted to engage the rod 20, and the rod is formed with openings adapted 5 for the reception of the screw; and by that means the rod is held into engagement with the socket.

The guide 23 is formed, as the guide 17, with the horizontally-aligned openings or 10 passages 24, adapted one for each section of the back 14, a set-screw 25 being provided whereby the guide is secured to the back, and whereby its adjustment thereon is permitted. Rigidly secured to the seat 3, at its forward 15 portion, and projecting downwardly therefrom, is the rod 26, which passes through an opening 27^a in the forward end of the bar 10, and by which the bar is guided and its proper position retained.

20 Thus it will be seen that by turning the shaft 6, by means of the seat 9, the seat will be raised or lowered, according to the direction in which the shaft is turned; and that this will be followed by a similar movement 25 of the back 14, owing to its connection with the shaft. By releasing the set-screw 27 of the guide 23, the guide may be disconnected from the rod 20, and the back, otherwise held thereby, released and allowed more movement. In addition to that, the guide may be 30 adjusted on the back and rod 20, and the spring properties of the back accordingly regulated.

The modification illustrated by Figs. 6, 7, 35 and 9, of the drawings, consists of an appliance whereby the chair is adapted for use as an office chair, and provided with arms, as is customary in such devices. This end is attained by securing to the bar 10 horizontally- 40 projecting arms 28, which are preferably six, in number, and which are arranged three on each side of the bar and project to the side of the seat 3. Formed in the outer ends of the arms 28 are the eyes 29, through which 45 the lower ends of the vertical rod 30 pass and in which the rods are secured by means of the nuts 31. From the arms 28 the rods 30 extend up vertically, and pass through the metallic bushings 32 in the seat 3, and above 50 the same to a point some distance above the seat 9. At a point in horizontal alignment with the seat 9 the rods 30 are rigidly secured to the castings 33, which are one for each side and each have the brace-rods 34 secured 55 thereto by screwing them into the castings and securing them with nuts 35. The rods 34 are two for each casting 33, and are secured at their inner ends to the clip 36, formed of two semicircular and flanged sections bolted 60 together and thereby held on the part 7, of the shaft 6. By these means the castings, and consequently the rods 30, are kept from useless lateral play. The seat 3 is formed with a depression 50 therein, adapted for the 65 reception of the clip 36, thus allowing the seat 9 to descend nearer the stationary seat 3 than would be possible were it not for this depre-

sion. A variation of this device consists of that shown in Fig. 8, where there is located on the periphery of the seat 9, and extending 70 its entire circumference, the section of channel iron 37, which is formed with the passage 38, substantially dove-tailed, and adapted for the reception of the heads 39 of the rods 40. The rods 40 may be of any reasonable number, preferably two, and extend outwardly to the castings 33, to which they are secured by means of the nuts 41. By these means the arms of the chair may be braced, and the seat 9 allowed to revolve freely, irrespective of the 80 rods 40, thereby raising or lowering the seat and its attached parts. The utility of this modified form of my invention will be apparent, and it is best adapted for use in offices and other places where arms are necessary or 85 desirable. It will be seen that the heads of rods 40 are capable of, and designed to move throughout the length of the slot or passage in the channel iron 37.

Having described my invention, what I 90 claim is—

1. In a chair, the combination of a frame, a threaded shaft arranged vertically therein, a seat connected to the upper end of the shaft, a back movable vertically on the frame, a bar 95 connecting the back and shaft, a rod arising vertically from the bar, and an adjustable connection between the rod and back, whereby the back is braced and its resiliency regulated, substantially as described. 100

2. In a chair, the combination of a frame, a threaded shaft movable vertically therein, a seat mounted on the shaft, a rod rigidly secured to the frame and projecting downwardly therefrom, a bar connected to the shaft 105 and movable longitudinally on the said rod, a back movable vertically on the frame and connected to the bar, whereby the back and seat are moved in unison, and a rod rigidly secured to and arising vertically from the bar 110 and an adjustable connection between the rod and back, whereby the back is braced and its resiliency regulated, substantially as described.

3. In a chair, the combination of a stationary seat supported on legs, a threaded shaft movable vertically therein, a seat proper fixed to the upper end of the threaded shaft, a bar loosely mounted on the lower end of the threaded shaft and below the stationary seat 120 and projected beyond the rear side thereof, a back slidably mounted on the rear side of the stationary seat and rigidly connected to the rear end of the bar, a series of rigid rods rigidly secured to the bar and projecting transversely from each side thereof, a vertically extending rod for each of the several transverse rods and rigidly connected thereto and two arms rigidly secured to the upper ends of the vertical rods and one at each side of the 130 chair and slidably connected to the stationary seat at opposite sides thereof, substantially as described. 135

4. In a chair, the combination of a station-

ary seat supported on legs, a threaded shaft movable vertically therein, a seat proper fixed to the upper end of the shaft, a bar loosely mounted on the lower end of the shaft and below the stationary seat and projecting to the rear side thereof, a back slidably connected to the rear side of the stationary seat and rigidly connected to the corresponding end of the bar, a series of rods rigidly connected to the bar and projecting transversely beyond either side thereof, a series of arm-supporting rods respectively connected to the rods of the bar and projecting vertically therefrom and slidably connected to the sides

of the stationary seat, a collar fitting loosely 15 on the threaded shaft and at the upper end thereof directly below the seat proper, brace- rods connected to the collar and to the arm- supporting rods, and arms mounted upon said arm-supporting rods, substantially as de- 20 scribed.

In testimony that I claim the foregoing as my own, I have hereto affixed my signature in the presence of two witnesses.
